UNITED STATES PATENT OFFICE

JOHN C. HARDIE, OF HELENA, MONTANA

PEA SHELLER

Application filed March 2, 1928. Serial No. 258,552.

This invention relates to vegetable hullers for shelling peas, beans and like pod enclosed berries, and pertains to an improved feeder for the type of machine disclosed in Letters Patent No. 1,615,081, granted me in the United States January 18, 1927.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit 15 it thereof.

For a full understanding of the invention and the merits thereof, reference is to be had to the following description and the drawings hereto attached, in which,—

20 Figure 1 is a front view of the machine, the feeder being omitted and a portion of the casing being broken away to show the outlet for the juices and the guard extending across the outlet.

25 Figure 2 is a vertical, central, transverse sectional view of the complete machine.

Figure 3 is an enlarged perspective view of the feeder.

Figure 4 is a front view of the complete 30 machine, the clamps and the outer portion of the operating shaft being broken away.

Figure 5 is an enlarged detail sectional view on the line 5—5 of Figure 4.

Figure 6 is an enlarged detail sectional 35 view on the line 6—6 of Figure 1.

Corresponding and like parts are referred to in the following description and designated in the several views of the drawings by like reference characters.

40 The machine includes a casing which is of sectional formation to admit of ready removal of the shelling or hulling rolls for cleaning. The members 1 and 2 comprising the casing are hingedly connected at 3 to admit of the member 1 swinging outwardly and rearwardly at its lower end. The shelling or hulling rolls 4 are journaled between the members 1 and 2, whereby to admit of their ready removal and replacement. The rolls 4 are geared at one end for

simultaneous rotation and the shaft of one is extended and provided with a crank handle 5. A standard 6 depends from an end of the casing and is provided at its lower end with a clamp 7 for convenience of 55 attaching the machine to a table 8 or analogous support. An opening 9 is formed in the rear member 1 of the casing for the discharge of the pods or hulls. A plate 10 is detachably fitted to the rear portion of the front member 2 in line with the lower end of the opening 9 and inclines downwardly and rearwardly to deflect the pods or hulls away from the machine. The deflecting plate 10 is provided at its upper end with 60 lugs 11 which engage a keeper 12 secured to the bottom side of the casing. The keeper 12 may consist of a plate soldered or otherwise secured to the bottom side of the casing to reinforce and strengthen the same. Portions of the plate 12 are spaced from the bottom of the casing to receive the lugs 11 whereby the deflecting plate 10 is detachably 65 connected to the casing to be readily removed for cleaning and easily replaced when required.

70 The opening formed in the front member 2 of the casing comprises a horizontally elongated portion 13 and a vertical portion 14. This opening is opposite the discharge opening 9 formed in the rear side of the casing and receives the feeder. Loops 15 project forwardly from the casing and are disposed at the sides of the vertical portion 14 of the feed opening. The feeder comprises a hopper 16, a spout 17 and a chute 18. The spout 17 is wide and flat and tapers throughout its length as indicated most clearly in Figures 3 and 4. The hopper 16 is narrow and tapers throughout its length and extends some distance above and forwardly of the spout 17. The outer or front wall of the spout 17 is cut away opposite the opening 13, as indicated at 17'. The inner or rear wall of the hopper 16 is cut away to register with the 80 portions 13 and 14 of the feed opening. The chute 18 is located about midway between the top and the bottom of the hopper 16 and when the parts are operatively positioned 85 this chute inclines rearwardly and down- 90

95

100

wardly, as indicated most clearly in Figure 2 of the drawings to direct the peas or beans to be hulled to the space formed between the hulling rolls 4. A space is left between the outer or front wall of the hopper and the adjacent end of the chute for the escape of any of the peas or seed that may fly forwardly after being released from the pods or hulls. Inwardly disposed flanges 19 at the top of the hopper 16 prevent any of the peas from discharging through the top of the hopper during the active operation of the machine. Openings 20 formed in the upper marginal portion of the outer or front wall of the spout 17 receive the loops 15, keys 21 being thrust through said loops to retain the feeder in place. The upper rear portion of the feeder is shaped to obtain a close fit against the front side of the casing, the chute 18 projecting through the feed opening 13-14 and terminating a short distance from the space formed between the shelling rolls 4 so as to deliver the peas or other pod enclosed vegetable to said rolls in proper position for hulling.

In the practical operation of the invention the peas or beans to be shelled are scalded and are supplied to the hopper 16 and are directed by the chute 18 to the shelling rolls 4 which are slowly rotated by means of the operating handle 5. The pods or hulls pass between the rolls 4 and are received upon the plate 10 and directed into a suitable receptacle not shown. The peas, berries or seeds released from the pods drop into the spout 17 and are directed into a suitable receptacle, not shown. The juices expressed from the pods or hulls collect in the bottom of the casing and pass to one end thereof and escape through an opening 22. A guard 23 secured to the bottom side of the casing opposite the opening 22 directs the juices outwardly so as to be received in a suitably placed receptacle, not shown. The arrangement is such that the feeder and the hulling rolls may be readily detached to admit of thorough cleaning which is essential in a machine of this nature. The parts may be readily assembled and made secure, as will be readily appreciated.

Having thus described the invention, I claim:

1. A machine of the character specified comprising vertically disposed hulling rolls, a casing enclosing the hulling rolls and having a front feed opening and a rear discharge opening, a plate secured to and reinforcing the lower part of the casing and having portions spaced therefrom adjacent the discharge opening, and a deflecting plate provided with lugs detachably engaging the spaced portions of said reinforcing plate to admit of its ready removal and replacement.
2. A machine of the character specified comprising vertically disposed hulling rolls,

a casing enclosing the hulling rolls and having a front feed opening including an upper narrow portion and a lower wide portion, a spout fitted to the casing about the lower wide portion of the feed opening, and having the upper portion of its front wall cut away to register with the upper narrow portion of the feed opening, a hopper mounted upon the front wall of the spout and extending upwardly and forwardly therefrom and having its rear wall cut away to register with the upper narrow portion of the feed opening and the cut away portion of the front wall of the spout and having its upper portion fitted to the casing about the said narrow portion of the feed opening, and a chute within and extending across the hopper and spout and inclining rearwardly and downwardly to deliver the peas between the hulling rollers and having its front end spaced from the front wall of the hopper.

In testimony whereof I affix my signature.

JOHN C. HARDIE. [L. S.]
